UNITED STATES PATENT OFFICE.

HENRY A. WEIHMAN, OF PHILADELPHIA, PENNSYLVANIA, ASSIGNOR TO
SIMONS, BROTHER & CO., OF SAME PLACE.

DESIGN FOR A CANE OR UMBRELLA HANDLE.

SPECIFICATION forming part of Design No. 19,993, dated July 1, 1890.

Application filed April 15, 1890. Serial No. 348,093. Term of patent 3½ years.

To all whom it may concern:

Be it known that I, HENRY A. WEIHMAN, a citizen of the United States, residing in Philadelphia, in the county of Philadelphia and 5 State of Pennsylvania, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

A is the body part, and is made like the inverted frustum of a cone, being larger at the 15 top, and is surmounted by a curved cap B, having a plain surface. The body part terminates at the bottom in an annular band C of plain surface, and is ornamented by spiral bands D and E, the former being made with

a plain surface and disjointed, as shown, and 20 the latter being made of highly-ornamented portions, forming a strong contrast between the adjacent spiral bands. Both the bands D and E are depressed or slightly grooved, though this may be confined to the bands D. 25

The handle is made of any suitable material.

Having now described my new design, what I claim as new, and desire to secure by Letters Patent, is—

30 The design for cane or umbrella handles, substantially as herein described and shown.

In testimony of which invention I have hereunto set my hand.

HENRY A. WEIHMAN.
